STEAM BATH HEATER

Bo Erik Nord and Karl Åke Jansson, Enkoping, Sweden,
assignors to A. B. Bahco, Stockholm, Sweden, a corpo-
ration of Sweden

Filed Mar. 27, 1964, Ser. No. 79,221

Term of patent 14 years

(Cl. D81—20)

Fig. 1.

FIGURE 1 is a perspective view of a steam bath heater, showing my design.

FIGURE 2 is an elevational view of the opposite side thereof.

The bottom, not shown, is flat and plain.

The broken lines shown on the drawing are for illustrative purposes only.

We claim:

The ornamental design for a steam bath heater as shown and described.
